UNITED STATES PATENT OFFICE

SARAH S. PETE, OF PITTSBURGH, PENNSYLVANIA

MECHANICAL TOY

Application filed March 12, 1930. Serial No. 435,278.

The invention relates to improvements in figure toys, an object being to provide a mechanical operated toy in the form of a miniature performer and an audience, the toy including a performer and a number of spectators, each being capable of movement to more effectually simulate the actions of real persons.

Another object of the invention is the provision of a toy as above stated, wherein the performer will move in representation of a dancer, during which time the spectators will remain inactive, but as soon as the performer stops, the spectators will move their arms with a swinging or clapping movement in imitation of applause.

With the above and other objects in view, the invention further includes the following novel features and details of construction, to be hereinafter more fully described, illustrated in the accompanying drawings and pointed out in the appended claims.

In the drawings:—

Figure 1 is a plan view of the toy.

Figure 2 is a section on an enlarged scale, the section being taken on the line 2—2 of Figure 1.

Figure 3 is an enlarged section on the line 3—3 of Figure 1.

Figure 4 is a sectional view on the line 4—4 of Figure 2, the scale being reduced.

Figure 5 is an enlarged section on the line 5—5 of Figure 2.

Referring to the drawings in detail where-in like characters of reference denote corresponding parts, the invention as illustrated comprises a housing 10, within which is enclosed the operating mechanism for the toy. The top of the housing represents a platform or stage 11, while the bottom 12 of the housing is removable and is secured in place by fastening devices 13.

Mounted upon the stage or platform is a performer 14 and an audience, the latter comprising a number of spectators 15 and 16. It is preferred that the spectators represent a mixed audience with the male and female figures alternately arranged. The spectators are seated in chairs 17 and are arranged in a semi-circle around the performer.

The performer as clearly shown in Figure 3 of the drawings has his arms 17 pivoted to his body by means of a pivot rod 19 and his elbows are provided with joints. The legs are pivotally secured to the body or torso 55 as shown at 21 and the knees are jointed as indicated at 22. The performer is provided with a suit 23.

The performer is supported upon an upwardly extending rod 24 which is carried at 60 the outer end of a lever 25. This lever is pivotally mounted as shown at 26 within a frame 27 and the latter is secured as shown at 28 to the bottom 12 of the housing.

The free end of the arm 25 is arranged in 65 the path of movement of pins 29. These pins project laterally from one side of a rotary member or wheel 30, being spaced circumferentially around the wheel for a portion of the distance only, the remaining portion being blank. Downward pivotal movement of the free end of the lever 25 is limited by a bar 31 and is yieldingly held in engagement with this bar by means of a spring 32.

The wheel 30 is mounted upon a shaft 33 and this shaft is mounted in suitable bearings provided in the frame 27. The wheel is provided with teeth 34 which are engaged by a pinion 35. This pinion is mounted on a shaft 80 36 which extends outward through the housing and is provided with a finger piece 37 by means of which it may be conveniently rotated. Secured upon this shaft is a coiled spring 38, one end being secured to the shaft 85 and the opposite end secured to a stationary member 39 carried by the frame 27. Thus, by rotating the shaft 36, the spring 38 may be tensioned and when released, will rotate the wheel 30. This rotation of the wheel 30 90 will cause the lever 25 to move pivotally when engaged by the pins 29, so that an up and down movement will be imparted to the rod 24 and this movement will cause a movement of the arms and legs of the performer 14, 95 in imitation of a man dancing.

Also pivotally mounted within the frame 27 upon a pivot 40 is a lever 41. The inner end of this lever is operated and is arranged in the path of movement of pins 42 which pro- 100

ject laterally from the wheel 30. The pins 42 are spaced around the periphery of the wheel a distance equal to the blank space between the end pins 29 upon the opposite side 5 of the wheel, so that when the lever 25 is pivotally moved by the pins 29, the lever 41 will be inactive, but as soon as pivotal movement of the lever 29 ceases, the lever 41 will be moved pivotally through contact by the 10 pins 42.

The outer end of the lever 41 carries a disk 43 from which extends a number of arms 44 which with the disk 43 simulates a spider-like element. These arms radiate from the 15 disk 43 and their outer outer ends have extending therefrom rods 45. These rods extend upward through the chairs 17 and through the body of the figures 15. The arms 46 of the figures 15 are pivotally connected to 20 said figures at the shoulder as indicated at 47. This pivotal connection is in the form of a substantially V-shaped rod 48 forming a crank which extends through openings 49 provided in the body of the figure 15. These 25 openings are of sufficient size to provide a loose fit. The upper end of the rod 45 is provided with an eye 50 which loosely receives the rod 48. When pivotal movement is imparted to the lever 41, an up and down movement 30 will be imparted to the rods 45 and as each of the figures 15 and 16 is provided with one of these rods, and as the arms of these figures are pivotally connected in the manner described, a swinging or clapping 35 movement will be imparted to the arms of the figures due to the shape of the rod 48. This will imitate the clapping or applause of an audience.

As previously stated, due to the relative 40 arrangement of the pins 29 and 42, the figures or spectators 15 and 16 will remain inactive during the dancing of the performer 14, but as soon as the performer stops dancing, the arms of the figures 15 and 16 will at once be 45 brought into action in imitation of applause.

The pinion 35 is rotatable upon the shaft 36 and is connected to said shaft by means of a pawl and ratchet mechanism 51. This permits the spring to be wound by the key 37 50 without actuating the operating mechanism. Unwinding of the spring however will cause the mechanism to operate as previously explained.

The invention is susceptible of various 55 changes in its form, proportions and minor details of construction and the right is herein reserved to make such changes as properly fall within the scope of the appended claims.

Having described the invention what is 60 claimed is:—

1. In a figure toy of the kind described, a platform, a plurality of images constituting figures on the platform, means for effecting a dancing action to one of the images, vertically shiftable arms on the remaining images,

cranks connected with the arms on the respective last designated images, a spider-like element having connection with the cranks and supported for rocking movement, and mechanism for actuating the first named means and also for rocking said element.

2. In a figure toy of the kind described, a platform, a plurality of images constituting figures on the platform, means for effecting a dancing action to one of the images, vertically shiftable arms on the remaining images, cranks connected with the arms on the respective last designated images, a spider-like element having connection with the cranks and supported for rocking movement, mechanism for actuating the first named means and also for rocking said element, and a motor for driving said mechanism.

3. In a figure toy of the kind described, a platform, a plurality of images constituting figures on the platform, means for effecting a dancing action to one of the images, vertically shiftable arms on the remaining images, cranks connected with the arms on the respective last designated images, a spider-like element having connection with the cranks and supported for rocking movement, and mechanism for actuating the first named means and also for rocking said element, the said mechanism being constructed to successively actuate the means and element.

In testimony whereof I affix my signature.
SARAH S. PETE.
